UNITED STATES PATENT OFFICE.

GEORGE ARTHUR GARTH, OF NUWARA ELIYA, CEYLON.

SIGNAL FOR USE ON VEHICLES.

1,399,955.

Specification of Letters Patent.

Patented Dec. 13, 1921.

Application filed January 31, 1921. Serial No. 441,318.

To all whom it may concern:

Be it known that I, GEORGE ARTHUR GARTH, a British subject, residing at Nuwara Eliya, Ceylon, have invented certain new and useful Improvements in Signals for Use on Vehicles, of which the following is a specification.

This invention is for improvements in or relating to signals, for use on vehicles, of the kind which indicate the direction in which the vehicle is proceeding. The object of this invention is to provide a construction of signal which shall be more compact and effective than those heretofore constructed both when used in the daylight and in the dark.

According to this invention, a device, for use on a vehicle to indicate the direction in which the vehicle is about to turn or is proceeding, comprises a single signal-member mounted so as to be capable of direction toward either side of the vehicle and means connected therewith whereby said member may be operated from a point 25 within the reach of a person in the vehicle.

Conveniently the signal member is automatically returned to its normal position when a particular signal is no longer required, but preferably it is capable of being 30 retained in any signaling position to which it may be brought until it is positively returned to the said normal position.

The signal-member may be rotatably mounted and operated by means of two 35 pulleys, one disposed within reach of a person in the vehicle and the other secured to the said member, which pulleys are connected with each other in such manner that any rotational movement of the one 40 is transmitted to the other.

These and other features of the invention will be pointed out in the claims and described with reference to the accompanying drawings which illustrate two constructions of signaling-device according to this 45 invention, and in which:—

Figure 1 is a vertical section through one construction of signal according to this invention, and a front view of its control 50 shown with part of the cover broken away.

Fig. 2 is a front view of the said signal shown partly cut away, and a side view of its control showing part of the cover removed.

Fig. 3 is a vertical section through a modi-

fied construction of signal, and a front view of its control.

Referring first to Figs. 1 and 2, the signal-member comprises a casing 11 in which a black arrow 12 is rotatably mounted in front of a white background. The arrow is secured on a spindle 13 borne in the bushed center 14 of a part 15 constituting the said background and is connected by a brace 16, curved for a purpose hereinafter to be described, with the center of a grooved pulley 17, the connection of the brace with the pulley being adjustable by means of a screw and slot securing means 18. The pulley is rotatably received in a cup-shaped 70 housing 19 formed at the forward end of a hollow boss 20. The latter is situated at the back of the casing 11 and extends partially therethrough to receive a securing nut 21. The said pulley has a spindle 22 75 extending axially from its rear face which spindle is received and borne in the hollow boss, extends therethrough, and has its extremity screw-threaded to receive lock-nuts 23 by means of which it is held in 80 position. Between the rear face of the pulley and the bottom of the cup-shaped end of the boss there is a coiled spring 24 which is secured at its outer end to the wall of the said cup-shaped end and at its 85 inner end is secured to a stepped portion of the spindle 22 in such manner as to tend always to move the pulley in the anti-clockwise direction. The pulley is operated against its spring through a Bowden wire 90 25 secured at one end to the periphery of the pulley and given a partial turn in the groove around the same.

The white background in front of which the arrow 12 rotates is of opal-glass and is 95 held in a metal rim 26 by bent-over lugs on the latter. The opal-glass lies against a padded stepped portion 27 of the front of the casing and within the latter, and a sheet of clear glass 28 is disposed in front 100 of it, the metal rim serving to space the two sheets of glass apart to clear the arrow 11. A bezel 29, which fits over the front of the casing is secured to the latter and bears upon the clear glass so as to hold it together with the metal rim and opal-glass 105 securely in position.

The signal-member is secured by the lug 30 in a prominent and unobstructed position on the front of a vehicle (in the case 110

of a motor vehicle it would be situated preferably on the center of the cowl immediately in front of the wind-screen) and is connected by the aforesaid Bowden wire with a 5 control which is situated within easy reach of a person in the vehicle. This control consists of a casing 31 having a removable front 32 and housing a double-grooved pulley 33 somewhat larger in diameter than the 10 signal pulley 17. This control pulley is formed with axial projections 34 one at each side which together constitute a spindle for the pulley and are received and borne in recesses 35 formed in the back, and 15 removable front respectively of the casing 31. The other end of the Bowden-wire aforementioned is secured to the pulley and is wound partially around the periphery thereof in one of the grooves. A finger- 20 piece 36 secured to the front face of the pulley, extends through a slot in the edge of the casing and forms the means whereby the control is operated, and a spring pressed 25 detent 37 within a recess formed radially in the periphery of the pulley enters notches 38, formed on the inside of the casing, as the arrow is brought into its various signaling positions. The strength of the detent spring is sufficient to retain the pulley and 30 with it the arrow in any signaling position against the action of the spring 24 until the finger-piece is again positively operated.

The operation of the signal is effected by moving the finger-piece in its slot so as to 35 wind the Bowden wire farther into groove on the pulley 33 and unwind it from the pulley 17, thus causing the latter to turn. The various positions of the arrow and their indication are as follows:— The arrow is di- 40 rected horizontally to the right when the vehicle is about to be turned to the right; horizontally to the left when the vehicle is proceeding in that direction; vertical (the normal position) when the vehicle is con- 45 tinuing straight ahead, and oblique to the left to give the "caution" signal which is used when it is desired to indicate that the vehicle is slowing down or stopping and when it is desired to warn other vehicles 50 that there is not room to pass. When the finger-piece is moved back the wire is slackened off the control-pulley 33 and is once more wound on the pulley 17 under the action of the coiled spring 24. Thus the ar- 55 row is returned.

It will be appreciated therefore that this construction is one that is compact, simple in construction and easy of operation, and is far more effective than the arm signal used 60 at present. Moreover, as with vehicles having closed bodies it is the practice of the driver to leave open some convenient part of the body in order that the arm signal may be given, the advantages of the closed body are not fully realized. With the pres-

ent invention, however, the body may be entirely closed without affecting the operation of the signal. Another advantage of this construction is that both hands of the driver are free to control the vehicle since 70 the hand is only engaged for an instant to give any particular signal.

To enable the device to be effective when it is dark, the signal-member is illuminated by an electric lamp 39 for which a holder 75 40 is provided, the arrow being quite opaque is defined clearly by the diffused light which passes through the opal-glass. It is to clear this lamp that the brace 16 is curved.

As it is necessary for the occupant of the 80 vehicle to have some idea of the position of the signal a small red glazed window 41 is provided which, in the normal position of the arrow is covered by a plate (not shown) secured to the brace 16, but for any other 85 position of the arrow is uncovered.

If desired a second signal somewhat smaller than the first may be provided at the rear of the vehicle (say, for instance on the rear off side mudguard). This second 90 signal can be operated from the same control as the first and for this purpose the control pulley is doubly grooved to carry another control wire.

The modification illustrated in Fig. 3 is 95 somewhat similar to the construction above described in that a rotating arrow is secured to a pulley which is connected by control wires to a control pulley. In this case however, the arrow is formed as an aperture 42 in a white opaque disk 43 which is secured on the front of a reflector 44, and with the latter rotates in a casing 45 behind a clear front glass 46. The said aperture is glazed with green glass and at the tail of the arrow 100 there is another small circular aperture 47 which is glazed with red glass. The reflector is rigidly secured at its rear end to the grooved signal pulley 48 and rotates therewith about a hollow bearing 49 which 105 extends through the back of the casing 45, the pulley being held on the bearing between a flange 50 and a collar 51.

The hollow bearing which extends 110 through the back of the casing extends also through a bracket 52 and a support 53 all of which are clamped tightly together against the collar 51. The bracket forms the means whereby the lamp is secured in position and the support is provided for one end of each 115 of two flexible tubes 54 which are adjustable therein by means of the screws 55. These tubes lead from the signal-member to a control 120 56 and inclose the control wires.

The control comprises a casing 57 in 125 which a second grooved pulley 58 of the same diameter as the first, is mounted to rotate. The shaft of this pulley extends through the front of the casing to receive an operating-arm 59.

A spring 60 is provided, within the casing, which is connected with the pulley-spindle at one end and is secured to the casing at the other and operates to return the latter to the normal position after a signal has been made. The control-wire takes the form of a flexible band 61 which is virtually endless and extends through the tubes 54 and around the two pulleys. It 10 is secured to each of the said pulleys at points 62 and 63 respectively so that should one pulley be rotated the movement is transmitted to the other.

This construction is similar in operation 15 to that of the other and the same signals are used, but the operating arm in this case affords the indication of the position of the arrow to the driver of the vehicle since the pulleys are so arranged that the said operating arm occupies the same position relatively to its casing as the arrow does to its casing. Moreover in this case the operating lever is held in position while a signal is made and returns to the normal position 20 when released. It will be appreciated that this construction affords an effective indication when operated during the day and to enable the signal to be effective when it is dark a light is arranged behind the disk. 25 This may take the form of an electric bulb 64 in the forward end of the hollow bearing or, in an emergency, may be a-candle in the holder 65.

It will be appreciated with this construction 30 that another signal conveniently of the first described construction, operatively connected with the front signal may be placed at the rear of the vehicle, in which case the arrow may be red and translucent so that it serves also as the rear light. If desired 35 a window of clear glass could be provided at the side of this rear signal so that the light is advantageously used to illuminate the number plate of the vehicle.

40 It is to be understood that the invention is not limited to the constructions described as these are given by way of example only.

What I claim as my invention and desire 45 to secure by Letters Patent is:—

50 1. A direction indicator comprising in combination, a casing having a glazed aperture at the front, a signal member disposed to the rear of but close to the said aperture, a rotatable member within and disposed 55 toward the rear of said casing, connecting means between the signal member and the rotatable member, and means for rotating the latter member.

60 2. A direction indicator comprising in combination a casing having a glazed aperture extending completely across its front, a signal member extending from one side to the other of and disposed to the rear of but close to the said aperture, a rotatable 65 member mounted upon the rear wall of the

said casing, connecting means between the signal member and the rotatable member and means for rotating the said latter member.

3. A direction indicator comprising in combination a casing having a glazed aperture extending completely across its front, a signal member extending from one side to the other of and disposed to the rear of but close to the said aperture, a plate to constitute a background for the eye situated behind the said signal member, a rotatable member mounted upon the rear wall of the said casing, connecting means between the signal member and the rotatable member, and means for rotating the said latter member.

4. A direction indicator comprising in combination, a casing having a glazed aperture extending completely across its front, a signal member extending from one side to 85 the other of and disposed to the rear of but close to the said aperture, a translucent plate to constitute for the eye a background situated behind the said signal member, a rotatable member mounted upon the rear 90 wall of the said casing, a light source disposed between the said background and rotatable member, connecting means between the signal member and the rotatable member, and means for rotating the said latter 95 member.

5. A direction indicator comprising in combination, a casing having a glazed aperture extending completely across its front, a signal member extending from one side to 100 the other of and disposed to the rear of but close to the said aperture, a translucent plate to constitute for the eye a background situated behind the said signal member, a rotatable member mounted upon the rear wall of 105 the said casing, an electric lamp situated between the said background and rotatable member and centrally in line therewith, connecting means between the signal member and the rotatable member which means are 110 carried around clear of said bulb, and means for rotating the said rotatable member.

6. A direction indicator comprising in combination, a casing having a glazed aperture extending completely across its front, 115 a signal member extending from one side to the other of and disposed to the rear of but close to the said aperture, a translucent plate to constitute for the eye a background situated behind the said signal member, a rotatable member mounted upon the rear wall of the said casing, an electric lamp situated between the said background and rotatable member and centrally in line therewith, a reflector connecting the said rotatable member to the signal member and inclosing the light source and means for rotating the said rotatable member.

7. A direction indicator comprising in combination, a casing having a glazed aper-

ture extending completely across its front, a signal member extending from one side to the other of and disposed to the rear of but close to the said aperture, a translucent plate 5 to constitute for the eye a background situated behind the said signal member, a rotatable member mounted upon the rear wall of the said casing, an electric lamp situated between the said background and rotatable 10 member and centrally in line therewith, a substantially parabolic reflector having the lamp at its focus and connecting the said rotatable member to the signal member and inclosing the light source and means for rotating the said rotatable member.

8. A direction indicator comprising in combination, a casing having a glazed aperture at the front, a signal member disposed to the rear of but close to the said aperture, 20 a pulley disposed toward the rear of the said casing, connecting means between the signal member and the pulley, a hand operable control pulley pivotally mounted, means for mounting the control pulley at a distance 25 from the signal casing, and means operatively connecting the two pulleys.

9. A direction indicator comprising in combination, a casing having a glazed aperture at the front, a signal member disposed to the rear of but close to the said aperture, 30 a pulley disposed toward the rear of the said casing, connecting means between the signal member and the pulley, a hand operable control pulley pivotally mounted, 35 means for mounting the control pulley at a distance from the signal casing, and an endless wire band surrounding the two pulleys and attached to a point on each of their peripheries.

40 10. A direction indicator comprising in combination, a casing having a glazed aperture at the front, a signal member disposed to the rear of but close to the said aperture, a pulley mounted upon a member carried by 45 the rear wall of the casing, connecting means between the signal member and the pulley, a hand operable control pulley pivotally mounted, means for mounting the control pulley at a distance from the signal casing, 50 and an endless wire band surrounding the two pulleys and attached to a point on each of their peripheries.

11. A direction indicator comprising in combination, a casing having a glazed aperture at the front, a signal member disposed 55 to the rear of but close to the said aperture, a plate to constitute for the eye a background situated behind the said signal member, a pulley mounted upon a member carried 60 by the rear wall of the casing, connecting means between the signal member and the pulley, a hand operable control pulley pivotally mounted, means for mounting the control pulley at a distance from the signal 65 casing, and an endless wire band surround-

ing the two pulleys and attached to a point on each of their peripheries.

12. A direction indicator comprising in combination, a casing having a glazed aperture at the front, a signal member disposed 70 to the rear of but close to the said aperture, a translucent plate to constitute for the eye a background situated behind the said signal member, a pulley mounted upon a member carried by the rear wall of the casing, a light source disposed between the background and the pulley, connecting means between the signal member and the pulley, a hand operable control pulley pivotally mounted, means for mounting the control 75 pulley at a distance from the signal casing, and an endless wire band surrounding the two pulleys and attached to a point on each of their peripheries.

13. A direction indicator comprising in 85 combination, a casing having a glazed aperture at the front, a signal member disposed to the rear of but close to the said aperture, a translucent plate to constitute for the eye 90 a background situated behind the said signal member, a pulley mounted upon a member carried by the rear wall of the casing, a light source disposed between the background and the pulley and carried by the member about which the pulley rotates, connecting means between the signal member and the pulley, a hand operable control pulley pivotally mounted, means for mounting the control pulley at a distance from the signal 95 casing, and an endless wire band surrounding the two pulleys and attached to a point on each of their peripheries.

14. A direction indicator comprising in combination, a casing having a glazed aperture at the front, a signal member disposed 105 to the rear of but close to the said aperture, a translucent plate to constitute for the eye a background situated behind the said signal member, a pulley mounted upon a member carried by the rear wall of the casing, a light source disposed between the background and the pulley and carried by the member about which the pulley rotates, connecting means between the signal member and the pulley which means are carried 110 around clear of said bulb, a hand operable control pulley pivotally mounted, means for mounting the control pulley at a distance from the signal casing, and an endless wire band surrounding the two pulleys. 115

15. A direction indicator comprising in combination, a casing having a glazed aperture at the front, a signal member disposed to the rear of but close to the said aperture, a translucent plate to constitute for the eye 125 a background situated behind the said signal member, a pulley mounted upon a member carried by the rear wall of the casing, a light source disposed between the background and the pulley and carried by the member about 130

which the pulley rotates, a reflector connecting the pulley to the signal member, a hand operable control pulley pivotally mounted, means for mounting the control pulley at a 5 distance from the signal casing, and an endless wire band surrounding the two pulleys.

16. A direction indicator comprising in combination, a casing having a glazed aperture at the front, a signal member disposed 10 to the rear of but close to the said aperture, a translucent plate to constitute for the eye a background situated behind the said signal member, a pulley mounted upon a mem-

ber carried by the rear wall of the casing, a light source disposed between the background and the pulley and carried by the member about which the pulley rotates, a substantially parabolic reflector having the lamp at its focus and connecting the pulley to the signal member, a hand operable control pulley pivotally mounted, means for mounting the control pulley at a distance 15 from the signal casing, and an endless wire band surrounding the two pulleys.

In testimony whereof I affix my signature. 20
GEORGE ARTHUR GARTH. 25
